UNITED STATES PATENT OFFICE

JOSEPH H. LEVI, OF WASHINGTON, DISTRICT OF COLUMBIA

DESIGN FOR A FINGER RING

Application filed October 5, 1932. Serial No. 45,229. Term of patent 14 years.

To all whom it may concern:

Be it known that I, JOSEPH H. LEVI, a citizen of the United States, residing in the city of Washington, District of Columbia, have invented a new, original, and ornamental Design for a Finger Ring, of which the following is a specification, reference being had to the accompanying drawing forming a part thereof.

Figure 1 is an edge elevation of a ring made in accordance with my design;

Figure 2 is a similar view taken at right angles to that of Figure 1, looking in the

direction of the arrow A, as seen on Figure 1;

Figure 3 is a top plan view of the ring; and Figure 4 is a perspective view thereof.

My finger ring consists of a single strand of metal wrapped substantially helically with the convolutions thereof entwining one another and having the appearance of two crossed and intersecting rings.

I claim:

The ornamental design for a finger ring, as shown and described.

JOSEPH H. LEVI.
